UNITED STATES PATENT OFFICE.

WILLIAM B. McCARTY, OF LAVELLE, PENNSYLVANIA.

AIR-DRAFT ATTACHMENT FOR CHIMNEYS.

Application filed March 20, 1923. Serial No. 626,257.

To all whom it may concern:

Be it known that I, WILLIAM B. McCARTY, a citizen of the United States, residing at Lavelle, in the county of Schuylkill and 5 State of Pennsylvania, have invented certain new and useful Improvement in Air-Draft Attachments for Chimneys, of which the following is a specification.

My invention relates to chimney attachments for effectively creating an air draft therein for assisting in the up flow of the smoke and gases within the chimney.

A further object of my invention is the provision of such an attachment that is 10 extremely simple of construction, the same being readily adapted for attachment to and detachment from the upper ends of chimneys for effectively creating an air draft therein, for the above ascribed purposes.

The nature and advantages of the invention will be better understood when the following detailed description is read in connection with the accompanying drawings, 15 the invention residing in the construction, combination, and arrangement of parts as claimed.

In the drawings forming part of this application, like numerals of reference indicate similar parts in the several views, 20 and wherein:-

Figures 1 and 2 are front and side elevational views respectively of an attachment constructed in accordance with this invention, the same being shown as positioned upon a chimney.

Figure 3 is a vertical transverse cross sectional view of my chimney attachment and taken upon the line 3-3 of Figure 1.

Figure 4 is a perspective view of the air controlled damper constituting a part of the invention shown in Figures 1 to 3 inclusive, and

Figure 5 is a vertical longitudinal cross sectional view of a slightly modified form of attachment.

With particular reference to the form of the invention shown in Figures 1 to 4 inclusive, the same constitutes the provision of an angular shaped hood or cap 5, the top wall of which is formed with an opening 6, this opening being surrounded by a vertically extending angular neck 7, the same being formed integrally upon the said 55 top wall of the hood or cap 5. The upper end of this neck 7 is formed with relatively

larger V shaped cut outs 8 upon the front and rear walls thereof, and loosely, pivotally mounted within the neck 7, and adjacent the upper end thereof is a damper 60 plate 9.

This damper plate 9 may be and preferably is of a form as shown in Figure 4, and is of such a length as to have the upper end thereof project externally of said 65 neck 7. The upper opposite sides of the damper plate 9 is formed with reversely bent curved wings 10 for purposes herein-after described, and in view of this description, it will at once be apparent that when 70 my attachment is positioned upon a chimney A and the wind is blowing in the direction of the arrows shown in Figure 3, the damper plate will be swung upon its pivot to a position as per this figure. A slight 75 vacuum will be resultant between the projecting end of the damper and the adjacent portion of the neck 7 will consequently draw in the smoke and gases upwardly within the chimney A, whereby the same will pass 80 outwardly through the adjacent cut out portion 8 in said neck 7. The wings 10 upon the projecting upper end of this damper are for the purpose of controlling the movement of the same upon its pivot when the 85 wind is blowing in a direction at right angles to said damper.

The form of the invention shown in Figures 1 to 4 inclusive is adapted for attachment to square or angular shaped chimneys, 90 and in the modification, Figure 5, the hood or cap 5' is rounded as is also the neck 7'. In this form of the invention, the end of the damper 9' within the neck 7' is pointed as shown for allowing the free pivotal movement of the damper within said neck.

In view of the above description, it is believed by me that the advantages and operation of a chimney attachment constructed in accordance with this invention will 100 be readily appreciated by those skilled in the art, and although I have herein shown and described the preferred embodiment of the present invention it is nevertheless to be understood that minor changes may be 105 made therein, without departing from the spirit and scope of the invention as claimed.

Having thus described my invention, what I claim as new, and desire to secure by Letters-Patent is:

A chimney attachment comprising a hood having a vertically disposed hollow neck

mounted upon its top and at the center thereof, the neck being provided at its upper end and at opposite sides with recesses leading in from the upper end of the neck, a rod disposed transversely across the interior of the neck and spaced below the lower edges of the recesses and parallel with the side walls of the neck provided with the recesses, a damper plate having intermediate curved portions bowed in opposite directions and disposed around the sides of the rod and loosely mounted thereon, the lower portion of the plate being received within the lower portion of the

neck, and the upper portion of the plate 15 extending above the upper edges of the neck, that portion of the plate which projects above the neck being provided at its opposite end with curved extensions disposed in opposite directions from the plate, 20 said extensions being spaced above the upper edges of the neck and disposed toward the side walls of the neck having the recesses, and the center of gravity of the plate being disposed above the rod. 25

In testimony whereof I affix my signature.

WILLIAM B. McCARTY.
